UNITED STATES PATENT OFFICE.

JOHN SCHADE, OF HOLYOKE, MASSACHUSETTS, ASSIGNOR TO NATIONAL BLANK BOOK COMPANY, OF HOLYOKE, MASSACHUSETTS, A VOLUNTARY TRUST ASSOCIATION OF COPARTNERSHIP HAVING AS TRUSTEES J. W. TOWNE, F. B. TOWNE, E. S. TOWNE, J. M. TOWNE, AND F. W. WILSON.

LOOSE-LEAF BINDER.

1,270,974.

Specification of Letters Patent. Patented July 2, 1918.

Application filed July 17, 1917. Serial No. 181,060.

To all whom it may concern:

Be it known that I, JOHN SCHADE, a citizen of the United States, residing at Holyoke, Hampden county, State of Massachusetts, have invented certain new and useful Improvements in Loose-Leaf Binders; and I do declare the following to be a full, clear, and exact description of the invention, such as will enable others skilled in the art 10 to which it appertains to make and use the same.

This invention relates to certain details in connection with the manufacture of loose leaf binders and more particularly those of 15 the transfer type which employ covers secured to bars; the invention being a special form and pattern of metal cap which is designed to cover the tubes at the ends to present an artistic appearance, at the same 20 time reinforcing the tube, securing a construction which is cheap to manufacture, handsome in appearance and capable of 25 withstanding hard use. The invention also provides a novel means of securing the cap to the tube.

In the drawings—

Figure 1 is a fragmentary top elevation of a binder having the present invention incorporated therein;

Fig. 2 is a sectional view on line 2—2 of Fig. 1;

Fig. 3 is a similar view on line 3—3 of Fig. 2;

Fig. 4 is a detailed elevation of the end 35 cap showing the preferred form of the invention;

Fig. 5 is an end elevation thereof;

Fig. 6 is a side elevation of a slightly modified embodiment of the invention; and

Fig. 7 is an end elevation thereof.

Referring more particularly to the drawing, the numeral 1 designates the top bar of a top or end lock binder of that type embodying a base and spaced upstanding 45 posts which pass through perforations 2 in said top bar, the latter being hingedly connected to the cover section 3 by the fabric, as at 4.

The top bar is preferably formed from a 50 piece of sheet metal bent into a flattened tubular casing, the edges of which are free as depicted in Fig. 3. Adjacent each end of

this casing is provided a pair of openings 5, one in the upper wall and the other in the lower wall in coincidence with the first 55 opening.

The end cap 6 may also be made of sheet metal, and is formed with the rounded exterior surface which presents a neat finish for the bar. In the preferred form the cap 60 has depending end walls 7 which extend inwardly over and embrace the exterior of the bar 1, the intermediate side walls being in-turned to form abutments or shoulders 9 and are then extended in parallel relation 65 from the cap body into the end of the bar 1, as at 10. The side walls 10 have locking spurs 11 lanced or struck out therefrom, the same extending outwardly toward the cap body and possessing sufficient resiliency to 70 spring into the openings 5 for interlocking with the top bar. The side walls preferably extend from one end portion only of the body so as not to interfere with the internal mechanism not shown, a key-hole 12 being 75 provided in the opposite end portion of the cap body for access to the latter.

In operation, the fabric covering 13 for the top bar is slightly extended beyond the latter and turned inwardly and the end cap positioned on the bar so that the spurs interlock in the openings 5, the shoulders 9 engaging the turned over edge of the fabric covering to securely clamp the same against the end of the bar.

In the modification, a reversal of the parts is provided in which the end walls 14 are inturned to form shoulders 15 and are lanced to provide the locking spurs 16, the side walls 17 extending over the exterior of the 90 bar to embrace the fabric covering.

To remove the end cap, any suitable tool, such as an awl, may be pressed against the locking spurs to force the same inwardly from interlocking engagement with the bar 95 after which the cap may readily be removed.

In either form it is not essential to even-up the fabric with the ends of the top bar to prevent the same from becoming wrinkled as is now the case. The tubular casing is 100 rendered practically as strong as the drawn or seamless tubing formerly used because of the stiffening or reinforcing capacity of the end caps in that the latter embrace the

exterior of the casing to prevent expansion and also support the upper and lower walls of the casing from within against collapsing.

While I show the cap with spurs to secure the same, it is evident that I might omit this feature and hold it by other means, namely rivets, welding, brazing, soldering, &c., but still retain the other main features of this cap design whereby it engages the tube both inside and outside, thus preventing it from collapsing or expanding.

What is claimed is:

1. In a loose leaf binder, a bar comprising a flattened tubular casing having openings in its upper and lower walls and adjacent one end, a fabric covering for the bar extended over said end thereof, and a sheet metal end cap, cut and stamped to form a body having a pair of opposing and depending walls extending inwardly over and embracing the outer surface of the fabric covering, and a second pair of opposing walls inturned to provide shoulders and extended downwardly inside the casing, said second walls having spurs stamped therefrom to interlock in the casing openings for holding the end cap on the bar and the shoulders against the end of the bar to clamp the fabric covering.
2. In a bar for loose leaf binders, a casing bent from sheet metal into tubular form and provided with opposing openings adjacent an end, a fabric covering for the casing having its end inturned over the end of the casing, and an end cap having means embracing both the interior and exterior of the casing for securing the fabric thereto.
3. In a bar for loose leaf binders, a casing bent from sheet metal into tubular form and provided with opposing openings adjacent an end, a fabric covering for the casing having its end inturned over the end of the casing, and an end cap having opposing walls inturned to provide shoulders for clamping the fabric against the end of the casing and means on the walls for interlocking in the casing openings to secure the end cap in place.
4. In a bar for loose leaf binders, a casing

bent from sheet metal into tubular form and provided with opposing openings adjacent an end, an end cap having opposing walls inturned to provide shoulders which set snugly against the end of the casing and spurs struck out from the walls for interlocking with the casing openings.

5. In a bar for loose leaf binders, a casing bent from sheet metal into tubular form and provided with opposing openings adjacent an end, a fabric covering for the casing having its end inturned over the end of the casing, and an end cap having opposing walls inturned to provide shoulders for clamping the fabric against the end of the casing and spurs struck out from the walls for interlocking with the casing openings, said cap also having interposed and opposing walls embracing the exterior of the casing and its fabric covering.

6. An end cap for the bars of a transfer binder comprising a body having opposing walls formed with struck out spurs and being outturned above the latter to form abutment shoulders.

7. An end cap for the bars of a transfer binder tube comprising a body having opposing walls formed with struck out spurs and being outturned above the latter to form abutment shoulders, and spaced opposing walls interposed between the others for embracing the exterior of a top bar.

8. In a loose leaf binder, a bar comprising a flattened tubular casing open at the ends, an end cap having opposing projections inturned to provide shoulders which fit snugly against the ends of the casing, while the projections themselves lie against the inner surface of the casing, said cap also having oppositely disposed parts which lie against the outer sides of the casing, and means for securing said projections to the casing.

In testimony whereof I affix my signature.

JOHN SCHADE.
